RIDGE PLATE

Roy E. Lushbaugh, New Albany, Ind.

Application June 13, 1946, Serial No. 676,389

2 Claims. (Cl. 135—15)

(Granted under the act of March 3, 1883, as amended April 30, 1928; 370 O. G. 757)

1 The invention described herein, if patented, may be manufactured and used by or for the Government for governmental purposes without the payment to me of any royalty thereon.

This invention relates to a ridge plate, and more particularly to a hardware element for the attachment of tent lines to an upright tent pole.

A conventional tent consists of canvas supported by one or more upright tent poles, and is held in upright position by a number of lines attached at one end to the canvas and at the other end to tent pegs driven into the ground. This method of support has the disadvantage that it imposes a great strain on the canvas and leads to its quick deterioration at the points of attachment of the lines. Tents of the non-pyramidal or wall type have at least two main upright poles and a vertical ridge pole joining the main upright poles; the conventional ridge pole is weighty, and in case of accidental collapse of the tent is apt to injure the occupants of the tent or the objects stored therein. It has been proposed to overcome these and other disadvantages of conventional tents by rigging the upright pole or poles by means of tent ropes fastened to a perforated plate which is supported at the peak or tip of the upright pole. In this manner, the weight of the tent is made to be borne by the upright tent pole and not by the canvas. Considerable strain is imposed in such a construction on the plate which attaches the ropes to the upright pole.

It is an object of the present invention to provide a plate for the attachment of lines to an upright tent pole, which is constructed to withstand considerable loads without deterioration.

Another object of this invention is a plate which is quickly and inexpensively stamped from a blank.

A further object of this invention is a plate for attachment of lines to an upright tent pole, having line attachment lugs or wings extending in the general direction of the ropes when the tent is erected.

Still another object of my invention is an item of hardware for use with tents which can be stacked compactly for purposes of shipment.

Other objects and advantages of my invention will appear from the following description thereof.

A ridge plate in accordance with my invention consists of a center portion having a single perforation therein for the accommodation of the tip of an upright pole, and perforated lugs

2 or wings extending from the center portion in the direction of the tent lines.

Two preferred embodiments of my invention are shown in the accompanying drawings as examples of my invention for the purpose of illustrating the same without, however, limiting the scope of my invention to these examples.

Fig. 1 is a perspective view of an embodiment of my invention.

Fig. 2 is a sectional view taken through lines 2—2 of Fig. 1.

Fig. 3 is a side elevation, and

Fig. 4 is a rear elevation of the embodiment illustrated in Fig. 1.

Fig. 5 is a perspective top view of another embodiment of my invention.

Fig. 6 is a sectional view taken through lines 6—6 of Fig. 5.

Fig. 7 is a side elevation, and

Fig. 8 is a front elevation of the embodiment illustrated in Fig. 5.

More particularly, a ridge plate according to my invention has a flat, relatively wide center portion 11 from which extend a front lug or wing 12, two side lugs or wings 13 and 14, and one rear lug or wing 15, all integral with center portion 11; each wing covering a substantial area, and side wings 13 and 14 being forwardly bounded by leading edges converging towards the lateral edges of front wing 12, so as to meet the latter, preferably at the outermost points of the forward boundary of flat center portion 11. The underside of the plate rests on upright pole A and has perforation 16 in its center portion 11, through which tip B of pole A extends. Each of the lugs or wings 12, 13, 14 and 15 has a perforation, designated 17, 18, 19 and 20, respectively. Tent lines, joined at one end to the ground by means of tent pegs (not shown), are attached to lugs or wings 12, 13 and 14; the line attached to lug or wing 12 through perforation 17 extends obliquely forwardly of the pole, while the lines attached to lugs or wings 13 and 14 through perforations 18 and 19 extend sideways. Lugs or wings 12, 13 and 14 are at fixed obtuse angles to center portion 11 of the plate, which substantially correspond to the direction of the pull exerted by the tent lines. This angular disposition prevents strain at the edges formed by the center portion and the lugs, and thus reduces the danger of deformation and failure of the plate. Lug or wing 15 extends rearwardly from the center portion 11 in the same plane as the latter for the purpose of attaching, through perforation 20,

50 a substantially horizontal tent line, the other end

40 or wings 12, 13 and 14; the line attached to lug or wing 12 through perforation 17 extends obliquely forwardly of the pole, while the lines attached to lugs or wings 13 and 14 through perforations 18 and 19 extend sideways. Lugs or wings 12, 13 and 14 are at fixed obtuse angles to center portion 11 of the plate, which substantially correspond to the direction of the pull exerted by the tent lines. This angular disposition prevents strain at the edges formed by the center portion and the lugs, and thus reduces the danger of deformation and failure of the plate. Lug or wing 15 extends rearwardly from the center portion 11 in the same plane as the latter for the purpose of attaching, through perforation 20,

45 a substantially horizontal tent line, the other end

50 of the plate, which substantially correspond to the direction of the pull exerted by the tent lines. This angular disposition prevents strain at the edges formed by the center portion and the lugs, and thus reduces the danger of deformation and failure of the plate. Lug or wing 15 extends rearwardly from the center portion 11 in the same plane as the latter for the purpose of attaching, through perforation 20,

of which is attached to a corresponding ridge plate supported by another upright pole (not shown). The horizontal tent line serves as a substitute for a ridge pole, as is more fully explained in co-pending application Serial No. 610,369, now Patent No. 2,493,749, dated January 10, 1950, Walter R. Brown, Roy E. Lushbaugh and John W. Cull, for a "Sectional Hospital Tent," filed August 11, 1945.

The lugs are preferably rounded in order to save material without sacrificing strength.

In a modification of a ridge plate in accordance with my invention, center portion 21, forward lug or wing 22, and rear lug or wing 25 correspond to center portion 11 and forward and rear lugs 12 and 15 of the first-described embodiment; center perforation 26, forward perforation 27 and rear perforation 30 correspond to center perforation 16, front perforation 17 and rear perforation 20 of the first-described embodiment. Side lugs or wings 23 and 24 of the modification resemble side lugs or wings 13 and 14 of the first-described embodiment, except that lugs or wings 32 and 34 are modified to have two perforations 28, 28', and 29, 29' in each. A pair of laterally extending tent lines may be attached to each side wing through its perforations, the lines forming an angle for the purpose of affording additional support to the upright pole. The angular relation between center portion and lugs of the modified plate corresponds to that of the center portion and lugs of the first-described embodiment.

By "tent lines," as used in this specification, I means ropes, web straps, and other equivalent devices. The lines may be attached to the perforations of the plate by being threaded therethrough, or by means of hooks, buckles or other equivalent devices.

It will be understood that while I have described the plate which forms the subject matter of my invention, as a ridge plate, it possesses utility in combination with a short upright or eave pole as well, and any changes in the design of the plate to fit the same to this or other equivalent uses obvious to the expert are likewise within the scope of my invention. Changes in dimensions, angles or proportions from the illustrated

and described embodiment of my invention, or changes in the number or location of perforations, may also be made without sacrificing any of the objects of my invention, and are therefore to be deemed to fall within the scope thereof. I therefore intend to be limited only by the appended claims.

I claim:

1. A ridge plate having a perforated flat and relatively wide center portion, a perforated forward wing integral with said center portion and extending downwardly at a fixed obtuse angle relative to said center portion, two perforated side wings integral with said center portion and extending downwardly from said center portion at opposite sides thereof at fixed obtuse angles to said center portion, the leading edge of each of said side wings converging towards a lateral edge of said forward wing, and a perforated rear wing extending rearwardly from said center portion in the same plane as said center portion.

2. A ridge plate having a perforated flat and relatively wide center portion, a perforated forward wing integral with said center portion and extending downwardly at a fixed obtuse angle relative to said center portion, two perforated side wings integral with said center portion and extending downwardly from said center portion at opposite sides thereof at fixed obtuse angles to said center portion, the leading edge of each of said side wings meeting a lateral edge of said forward wing at a point coinciding with an outermost point of the forward boundary of said center portion, and a perforated rear wing extending rearwardly from said center portion in the same plane as said center portion.

ROY E. LUSHBAUGH.
